UNITED STATES PATENT OFFICE.

CONRAD J. HEIDMEYER, OF ALLEGHENY, ASSIGNOR OF ONE-FOURTH TO
SAMUEL HARTMAN, OF PITTSBURG, PENNSYLVANIA.

MONUMENT.

SPECIFICATION forming part of Letters Patent No. 271,453, dated January 30, 1883.

Application filed September 23, 1882. (No model.)

To all whom it may concern:

Be it known that I, CONRAD J. HEIDMEYER, a citizen of the United States, and a resident of Allegheny, in the county of Allegheny and State of Pennsylvania, have invented 5 a new and valuable Improvement in Monuments; and I do hereby declare that the following is a full, clear, and exact description of the construction and operation of the same, 10 reference being had to the annexed drawing, making a part of this specification, and to the letters and figures of reference marked thereon.

The drawing is a vertical sectional view.

This invention relates to monuments; and 15 it consists of, as an improved article of manufacture, a hollow iron monument having its interior walls enameled with a vitreous substance and its exterior walls enameled by a similar substance in imitation of marble, slate, 20 granite, or the like, as will be hereinafter fully described and claimed.

In the accompanying drawing, the letter A designates a monument of ordinary form, which is built up of sections B B, of cast or wrought 25 iron. These sections are made hollow, and are enameled over the entire surface, inside and outside. The interior surface of the monument or section thereof is enameled in order to guard against rust or corrosion, and the exterior surface is protected in the same manner 30

and for the same purpose, the enamel of the exterior, however, being applied in such a manner as to represent a surface of marble, slate, granite, or other stone.

The enameling composition should be applied 35 to the iron-surface in the best manner known to those skilled in this art, the composition being fused upon the iron in a suitable furnace.

Name-plates and ornaments can be applied to these hollow monuments with great facility, 40 care being taken to cast the bolts or studs which are to serve as fastenings in the plate or other ornament, so that there will be no disfiguring projections.

Having described this invention, what I claim, 45 and desire to secure by Letters Patent, is—

As an improved article of manufacture, a hollow iron monument having its interior walls enameled with a vitreous substance, and its exterior walls enameled with a similar sub- 50 stance in imitation of marble, slate, granite, or the like, substantially as specified.

In testimony that I claim the above I have hereunto subscribed my name in the presence of two witnesses.

CONRAD JOSEPH HEIDMEYER.
